UNITED STATES PATENT OFFICE.

FRANK R. CARR, OF XENIA, OHIO.

PISTON-RING.

1,351,369.

Specification of Letters Patent. Patented Aug. 31, 1920.

Application filed December 18, 1919. Serial No. 345,707.

To all whom it may concern:

Be it known that I, FRANK R. CARR, a citizen of the United States, residing at Xenia, in the county of Greene and State of Ohio, have invented certain new and useful Improvements in Piston-Rings, of which the following is a specification.

This invention relates to new and useful improvements in piston rings for internal 10 combustion engines.

The object of the invention is to provide means inherent in the structure of the piston ring for increasing the efficiency of the engine. The means so inherent in the piston 15 ring structure consists in the provision of structural features which prevent any leakage of the compressed explosive mixture between the surrounding wall of the engine cylinder and the piston ring, and said structural features further relate to means for preventing any surplus of lubricating oil 20 from accumulating on the surrounding cylinder wall as shall be hereinafter more fully described in connection with the accompanying drawings.

Referring to the said drawings in general terms, Figure 1 is an elevation of the piston in connection with which my improved ring is exemplified. One of the rings is shown in 30 section while others appear full. Fig. 2 is an elevation of the piston ring removed from the piston, and Fig. 3 is a section of the piston ring on the line 3—3 of Fig. 2.

In a more particular description of the 35 invention similar reference characters will indicate the same parts in the drawings.

The ring —1— is cut through on one side to permit of the necessary compression and expansion when in the peripheral groove 40 —2— of the piston —3—. The said cut may be in the form of steps —4— or tapered abutting or matching edges —5—. Or the cut through the ring on one side may be in any form.

The more particular features of the ring —1— comprise the groove —6— in the upper edge of the ring. The inner wall of this groove is parallel to the axis of the piston or the ring itself, while the outer wall of the 50 said groove extends in an outer and upward taper to the periphery of the ring. The said groove —6— having these structural characteristics prevents any leakage of the explo-

sive mixture from the front of the piston around the periphery thereof, while the explosive mixture is being compressed by the piston. While the piston is moving on its compression stroke the fluid ahead of the said piston is deflected inwardly toward the center of the piston by the tapered wall of 60 the groove. This action materially relieves the pressure of the explosive mixture around the periphery of the piston and consequently the tendency to leakage around the piston and between it and the walls of the cylinder. 65 The groove —7— in the lower part of the periphery of the ring is an oil groove and its construction as shown in Fig. 3 is in the form of an upper horizontal wall and a downwardly and outwardly tapered wall at 70 the bottom. Any surplus of the lubricating oil is prevented from accumulating on the surrounding wall of the cylinder above the piston owing to the formation of the said groove —7—. It will be noted that the 75 lower tapered wall of said oil groove terminates above the lower end of the ring which provides a peripheral surface at that point that engages the wall of the cylinder and prevents the oil emptying from the groove on 80 to the surrounding wall of the cylinder. The usual carbonization taking place in a cylinder of an internal combustion engine due to the admixture of the products of combustion with the lubricating oil adhering to the 85 walls of the cylinder and in the head thereof is very materially reduced owing to the formation of the said oil groove near the lower end of the ring surface.

A further feature which adds to the advantages of the ring is due to its being constructed in one piece with the said grooves —6— and —7— so arranged. The tendency for carbon to accumulate is materially less as compared with a ring constructed of 95 more than one integral part or in different parts. And in addition, through the instrumentality of the specially formed grooves, a ring having a maximum of compression capacity, and a decided retardation in the process of carbonization, is the result.

Having described my invention I claim:

The combination with a piston, of a one piece piston ring disconnected on one side, the said ring having an annular groove in 100 the upper face thereof, the inner wall of said

groove being parallel to the axis of the ring and the outer wall thereof being tapered outwardly and upwardly from the lower terminal of said inner wall to provide a deflecting surface for the explosive mixture while under compression, and an outer peripheral oil groove in said ring inclosed by an upper

horizontal wall and a lower outwardly and downwardly tapered wall, said last named wall being terminated above the lower end 10 of the ring, substantially as specified.

In testimony whereof I affix my signature.

FRANK R. CARR.
